INKING MECHANISM FOR ROTARY PRINTING MACHINES

Application filed September 19, 1928, Serial No. 306,832, and in Great Britain October 17, 1927.

This invention relates to improvements in inking mechanism for use in rotary printing machines, especially those of the type used for printing newspapers and similar products.

Many of these machines are supplied with ink by means of pumps which draw ink from a reservoir and force it through conduits to an ink rail which is supported in close proximity to an ink distributing cylinder. The ink rail is constructed with chambers disposed longitudinally on the side which is adjacent to the cylinder, the length of the chambers usually corresponding to the width of a column of the printing. Each of the chambers is connected by a conduit to a pump, and has an orifice through which the ink is forced against the surface of the ink distributing cylinder.

In the past, machines having inking mechanisms of this type have had the ink rail fixedly supported; but it has been found that a better distribution of the ink is obtained and consequently better printing, when the ink rail is given a limited reciprocating movement lengthwise of the cylinder.

It is an object of the invention to provide an improved inking mechanism that will produce a better distribution of ink on the inking cylinders, than is obtained with mechanisms heretofore known.

It is also an object of the invention to provide an inking mechanism of generally improved construction, whereby the device will be simple, durable and inexpensive in construction as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

Referring to the drawings:

Figure 1 is a side view of a portion of a

printing machine partly in section and partly in outline, showing the improved inking mechanism and cooperating parts of the machine.

Figure 2 is a longitudinal view of a portion of the improved inking mechanism as shown in Figure 1, this view depicting the apparatus as viewed in the direction of arrow 2 of Figure 1, and

Figure 3 is a horizontal view partly in section of the mechanism by means of which the ink rail is reciprocated, this view being taken as it appears on line 3—3 of Figure 1 and in the direction of the arrow.

In the drawings, 11 indicates one of the two side frames of the machine, in which are suitably supported, a primary ink distributing cylinder 12, a secondary ink distributing cylinder 13, and ink rollers 14, 15, 16, 17 and 18.

The ink cylinders 12 and 13 may be driven from any suitable shaft of the machine and in the preferred construction will both rotate at substantially the same peripheral speed. The roller 14 is driven by contact with cylinders 12 and 13, and the rollers 15, 16, 17 and 18 are driven by contact with the cylinder 13. Any or all of these rollers may be reciprocated along their axes, by suitable well known mechanism, to aid in evenly distributing the ink on the cylinder 13.

An ink feeding device 19 is formed with an ink rail 20 having a series of chambers, each with an orifice, one of which is shown at 21. These chambers are connected by conduits 22, with pumps, and a reservoir not shown on the drawings.

The ink feeding device is provided with slides 23 and 24, which are fitted to a frame 25, having guideways 26 and 27, and a gib 28. The frame 25 also has slides 29, fitted to ways 30 in the main frame. The rack 31, is secured to the frame 25 and meshes with the pinion 32, keyed to the shaft 33.

Brackets 34 and 35 are secured to the frame and provide bearings for the shaft 36, to which are secured the worm wheel 37, and the face plate 38. A pin 39 carrying a roller 40, is eccentrically mounted on the face plate,

and the roller operates in a groove 41, in the ink feeding device 19.

The worm wheel 42, is secured to the shaft of the cylinder 13 and meshes with the worm wheel 37. It will thus be understood that when the machine is running the shaft 36 will be driven and that the eccentrically mounted roller 40 will so act on the ink feeding device 19, that it will be reciprocated in the frame 25, parallel to the axis of the cylinder 12; thus moving the orifices of the ink rail along the cylinder 12 and distributing the ink thereon. From there the ink is taken off by the roller 14 from which it is transferred to the cylinder 13. The rollers 15, 16, 17 and 18 act to complete the distribution of the ink on the cylinder 13 from which it is then transferred to the printing plates by the usual form rollers.

It will be understood that a hand wheel or other suitable means may be connected to the shaft 33 and by rotating same, the ink rail 20 may be moved away from the cylinder 12, and allow access for cleaning or inspection, and it will be seen that the roller 40 will pass through the groove 41, offering no restrictions to the movement of the ink rail away from or back to the operating position.

What we claim is:

1. In an inking mechanism for printing machines, an ink distributing cylinder, an ink feeding device from which ink may be fed to the cylinder, means for moving the said feeding device toward and away from the cylinder, and means for reciprocating the feeding device, said reciprocating means being automatically engaged with and disengaged from the feeding device when it is moved respectively toward and away from the cylinder.

2. In an inking mechanism for a printing machine, an ink distributing cylinder, an ink rail adapted to be supplied with ink, orifices in said rail through which ink may be fed to the cylinder, and means for reciprocating the ink rail; said means including a roller mounted eccentrically to the rotating shaft and engaging the sides of a transverse groove in the said rail.

3. In an inking mechanism for a printing machine, an ink distributing cylinder, an ink feeding device from which ink may be fed to the cylinder, a transverse groove in the feeding device, a rotating shaft mounted with its axis substantially transverse to the axis of the ink cylinder, and a roller carried by the shaft and eccentrically supported with relation thereto; said roller being adapted to operate in the said groove and thereby reciprocate the feeding device.

4. In an inking mechanism for a printing machine, an ink distributing cylinder, an ink feeding device adjacent thereto, from which ink may be fed to the cylinder, and means for reciprocating the feeding device

lengthwise of the cylinder, said means being arranged to permit moving the said feeding device away from the cylinder and out of engagement with the reciprocating means.

In testimony whereof, we affix our signatures.

CECIL GEORGE QUICK.
EDWARD THOMAS MORRIS.
